UNITED STATES PATENT OFFICE

EDWIN BIRD WILSON, OF FOREST HILLS, NEW YORK, ASSIGNOR TO DESIGN LABORATORIES, INCORPORATED, OF NEW YORK, N. Y., A CORPORATION OF NEW YORK

ELECTRIC LIGHTING FIXTURE

Application filed March 18, 1927. Serial No. 176,442.

This invention relates to lighting fixtures of the general type disclosed in my copending application Serial No. 25,992, filed April 27, 1925 and relates more particularly to electric lighting fixtures, such as chandeliers, brackets, etc. constructed from sheet metal or other thin material.

The object of the invention is the provision of a method for cheaply and easily constructing lighting fixtures from sheet metal or other thin material.

I attain this object by fashioning from sheet metal a plurality of flat elements, cutting notches in the said elements and rigidly interlocking the elements by means of the notches therein. In constructing some forms of fixtures, I find it desirable to provide flexible ears on some of the elements, which may be bent to hold portions of the fixture together.

Other objects and advantages of my invention will be made clear by the following description taken in connection with the accompanying drawings.

25 In the drawings, Fig. 1 illustrates in elevation, a lighting fixture constructed in accordance with my invention.

Fig. 2 is a sectional view of the fixture shown in Fig. 1, looking along line A—A.

30 Figs. 3, 4, 5 and 6 are detail views of the elements making up the fixture shown in Fig. 1.

Fig. 7 shows in elevation a ceiling fixture constructed in accordance with my invention.

35 Figs. 8 and 9 are details of the elements making up the fixture shown in Fig. 7.

Fig. 10 is a view in elevation of another form of lighting fixture.

Fig. 11 is a plan view of the fixture shown 40 in Fig. 10.

Figs. 12, 13 and 14 are detail views of the elements making up the fixture shown in Fig. 10.

45 Fig. 15 illustrates a boudoir or table lamp constructed according to my invention.

Fig. 16 is a plan view of the lamp shown in Fig. 15.

50 Figs. 17, 18 and 19 illustrate a socket holding arrangement suitable for use with any one of the fixtures shown in Figs. 1 to 19.

Fig. 1 represents a bracket lighting fixture composed of five elements, two bulb shaped elements 1 and 2, a stiffening element 4, a spacer ring 3 and an escutcheon plate 5. All of these elements are rigidly interlocked and held together by means of notches, or slots, cut in the said elements, as best represented in Figs. 3, 4, 5 and 6. The bracket is assembled by interlocking elements 1 and 2 by means of slots 10, 12 and 20, 21, this being accomplished by placing element 2 beside element 1 on a line with slots 10 and 12 and at right angles to the plane of element 1, engaging the open ends of slots 12 and 21 and sliding the two elements together as far as the slots permit, then springing element 2 into a bow shape so that the open ends of the two remaining slots, 10 and 20 can be engaged one with the other, and allowing element 2 to resume its natural flat shape, which will cause the elements 1 and 2 to be firmly held against relative longitudinal displacement. Spacer ring 3 is then positioned in slots 11 and 22 by forcing the ring down over the top of the elements 1 and 2 and flexing the 55 said elements slightly to make their width small enough to allow the ring to slip into the slots 11 and 22. When the ring is finally in its proper position as shown in Fig. 1, it 60 serves, by means of slots 24 to hold the elements 1 and 2 against relative angular displacement. Stiffening element 4 is then interlocked with elements 1 and 2, this being 65 accomplished by sliding elements 4 and 1 together by means of slots 13 and 18, and at the same time bending the bifurcated end of element 4 downwardly and the notched end of element 2 inwardly so that by slight 70 manipulation the elements 2 and 4 will be rigidly interlocked and held by virtue of slots 75 19 and 23, thus holding the entire assembly 80 in its proper relation. Ears 14 and 25 of elements 1 and 4 are now passed through slits 85 26 and 27 in escutcheon plate 5 thus bringing the plate up against shoulders 15 of elements 1 and 4. When the escutcheon plate is 90 in its proper position the ears 14 and 25 are bent over against the plate thus holding the plate rigidly fixed to the rest of the assembly. 95 A lamp bulb 7 may be positioned within cut

out section 16 of elements 1 and 2. The bulb is held by a socket 6 seated in a pocket 17 in elements 1 and 2 and fed by current carried by a wire 8, which passes downwardly and outwardly through holes 9 in the element 5 4 and escutcheon plate 5 respectively, in such manner as to be hidden from view as completely as possible. The means for holding a bulb socket in pocket 17 is more clearly illustrated and described in connection with 10 Fig. 17.

Figs. 7, 8 and 9 show a ceiling fixture comprising three elements 28, 29 and 30 all held together by slots in like manner to the 15 bracket shown in Fig. 1.

Figs. 10, 11, 12, 13 and 14 show another form of ceiling fixture consisting of four elements 31, 32, 33 and 34. This fixture is assembled in substantially the same manner as 20 the bracket shown in Fig. 1 except that in order to position the spacer ring 34 it is necessary to bend projections 34; of elements 31 and 32, inwardly in order to allow ring 34 to drop past them, after which they are bent 25 back into their original position thus holding the ring 34 in its proper position.

Figs. 15 and 16 show a boudoir or table lamp consisting of two bulb shaped elements 39 and 40 and a heavy base plate 41. These 30 elements are assembled in substantially the same manner as the ceiling fixture shown in Fig. 7.

Figs. 17 and 18 show a socket holding arrangement for securing a lamp socket in any 35 one of the forms of lighting fixture which I have illustrated. Reference numeral 49 indicates a square nut which fits tightly in a cut out pocket 48, in the elements 46 and 47, and is retained in the pocket by means of 40 projections 50 of the elements 46 and 47. The socket is securely attached to the nut 49, preferably by means of a short screw threaded nipple and is held in proper alignment by additional projections, 51, which frictionally 45 engage the socket under pressure due to the resiliency of the elements 46, 47 and the projections 51.

Fig. 19 shows a socket holding means utilizing a hexagonal nut which would be used 50 in the case of a fixture made of three intersecting elements rather than two.

Fixtures constructed in accordance with my invention can be cheaply, easily, and strongly constructed from sheet metal, without 55 the necessity of soldering, welding or riveting any of the component parts thereof. While such fixtures are extremely light and inexpensive, they give the effect of solidity and massiveness, due to the illusion produced 60 by the intersecting elements. While I have illustrated several fixtures made of two intersecting elements, it will be found that for best effects in some designs, three or more interesting elements should be used.

65 It will be obvious to those skilled in the

art that the invention is capable of a wide variety of modifications and adaptations and that the present disclosure is intended merely to illustrate its nature without limiting its scope, which is defined in the following 70 claims.

What I claim is:

1. A socket holder for a lighting fixture, consisting of a plurality of plates having a common point of intersection, each of said 75 plates having a pocket cut therein, a nut seated tightly in the common pocket of said plates, a lamp socket secured to the said nut by means of a threaded nipple, means for retaining the nut in its proper position and preventing longitudinal movement thereof and means attached to the walls of said pocket for supporting the said socket.

2. A lamp fixture consisting of two plates intersecting each other at right angles, a 80 substantially U-shaped opening in each of said plates, a pocket at the bottom of each opening a nut tightly held in the bottom of the pockets, means for preventing longitudinal movement of said nut and a lamp socket secured to said nut by means of a threaded 85 nipple.

3. In a lighting fixture an escutcheon plate, a plurality of profile members having slots 90 therein, said members being interlocked solely by means of said slots, one of said members comprising a light holding portion, and a bracket arm at an angle to and at one end of said light holding portion, a flat member intersecting said bracket arm and cooperating therewith firmly to hold the profile members to the escutcheon plate, a notched perforated member engaging said profile members and cooperating with said flat member to hold said profile members in fixed angular 95 relation to one another.

4. In a lighting fixture, a first set of profile members having slots therein and adapted to interlock with one another solely by means of said slots, one member of said first set of profile members having an angular portion cooperating and interlocking with an auxiliary profile member to form a second set of profile members, said auxiliary profile member intersecting and interlocking with another member of said first set of profile members, to hold the component parts of the entire fixture in fixed angular relation to one another.

5. In a lighting fixture, a plurality of profile members, each having a socket receiving opening therein, a first series of notches in the members whereby they may be interlocked and held against lateral displacement, one of said members having an angular extension, an auxiliary member, a main notch in said extension and in said auxiliary member whereby the auxiliary member may be interlocked with the extension and prevented 125 from lateral movement with respect thereto, 130

secondary notches in said auxiliary member at right angles to said main notch, and cooperating notches in one of said profile members at right angles to said first series of notches, said secondary and cooperating notches serving to interlock the auxiliary member and profile members and hold them against longitudinal displacement.

In testimony whereof, I have signed my
10 name to this specification this 15th day of
March, 1927.

EDWIN BIRD WILSON.
